LIFE SAVING DEVICE

Application filed May 9, 1930. Serial No. 450,923.

This invention relates to life saving devices and more particularly refers to improvements in life savers adapted for individual use.

5 Life savers of the type ordinarily found on board ships and other places where safety provisions have to be made for the lives of the passengers are usually in the form of flexible belts comprising a series of blocks made of buoyant material such as cork, for instance, said blocks being connected to one another by means of a covering of flexible fabric.

15 These belts are to be worn around the waist so as not to interfere with the movements of the arms or other parts of the body; but I have found in practice that life savers of this description are open to two very serious objections. One is, that in order to place them in position it is generally necessary to have the assistance of another person and this, during the excitement of a wreck can rarely be secured. The other objection is that the buoyancy imparted by the device 20 to the body of the wearer is applied in the wrong place tending as it does to raise the middle part of the body to the water level, while the head tends to become submerged 25 on account of its weight.

30 In other words, the life saving belt and the head of the wearer form a turning couple which makes it very difficult for the wearer to keep his mouth and nose above water and which eventually may be the direct cause of his drowning.

35 There are other types of life savers used in the form of a buoyant ring forming a support for the underarms of the person clinging to it; however, life savers of this type interfere very seriously with the freedom of movement of the arms and make it very difficult for the person to stay afloat when fatigue begins to be felt.

40 I have also observed that when a wreck occurs, many persons are thrown into the water, and unless help reaches them very promptly, many succumb even though they may have succeeded in keeping afloat for a considerable time. In such cases, thirst is 45 the chief cause of exhaustion and ultimate

death of the victims especially in choppy seas where salt water is likely to be swallowed during the struggle for keeping afloat.

I have therefore developed the life saving device forming the subject of the present 55 invention with a view to correcting all these shortcomings of devices heretofore in use.

The primary object of the present invention is to provide a life saving device of a novel and improved design adapted to apply 60 the buoyant force to the body of the wearer at the proper place without interfering with the freedom of his movements.

Another object is to provide a life saving 65 device of a novel and improved type adapted to be quickly inserted in position without any difficulty and without the necessity of outside help.

A further object is to provide in a life saving device of the character specified a closed 70 compartment or compartments in which a suitable liquid can be stored as well as valuables or food or money, the compartment containing liquid being provided with a suction pipe extending to a point within convenient reach of the mouth of the wearer.

75 A still further object is to provide a life saving device comprising front and rear buoyant members equipped with suitable means for securing the device to the body 80 of the wearer, said device being preferably of a collapsible type so as to form a compact unit simulating a bag or similar article when in its closed position.

85 Still another object is to provide a life saving device adapted to be applied to the upper part of the body of the wearer, said device comprising a rear member provided with a head rest affording a support for the head in a reclining position.

90 Other objects and advantages of the present invention will more fully appear as the description proceeds and will be set forth and claimed in the appended claims.

95 My invention is illustrated by way of example in the accompanying drawings, in which:

100 Fig. 1 is a view in perspective of a collapsible device embodying my invention in its closed position;

Fig. 2 is a view in perspective of the same in its expanded position;

Fig. 3 is a vertical section of the device in its closed position;

Fig. 4 is a vertical section of the same in its open position;

Fig. 5 is an expanded view in perspective of the two halves composing the device;

Fig. 6 is a diagrammatic illustration of a swimmer wearing a life saving belt of the ordinary type;

Fig. 7 is a similar view of a swimmer wearing the life saving device forming the subject of the present invention;

Fig. 8 is a side view of the upper part of a person wearing my improved device showing how the head may be reclined rearwardly against the head rest with which the device is equipped;

Fig. 9 is a view in perspective from the rear of the upper part of the body of the wearer illustrating the manner of holding the device in position;

Fig. 10 is a fragmentary view in perspective from the front of the upper part of the body illustrating the position of the suction tube within reach of the mouth of the wearer;

Fig. 11 is a view in perspective of a device embodying my invention in a modified form;

Fig. 12 is a side view of the upper part of a person wearing the device shown in Fig. 11.

My improved device consists of two halves 10, 11 each in the form of a relatively shallow water tight chamber having a substantially rectangular outline. Said two halves which are the members conferring buoyancy to the device have the same height and width so that when they abut against each other they form a structure such as shown in Fig. 1, having the general appearance of an ordinary hand bag.

The device may be retained in its closed position by providing the same with any suitable locking arrangement, said locking arrangement being easily releasable by hand and permitting of the two members being moved apart as shown in Fig. 2.

In said figure, it will be observed that each buoyant member has its inner surface provided with recesses such as 12, 13, 12', 13' at its upper corners, said recesses providing housings for straps 14, 15 connecting the upper portion of one member to the upper portion of the other member.

In a similar manner, said two members are provided with similar recesses 16, 17, 16', 17' at their lower corners, said recesses being adapted to form housings for side straps such as 18, 19, 18', 19' which may hang down therefrom when the device is in its open position the outer ends of said straps being connected by rings 20, 20'. Said rings are also each provided with an open link 21, 21' through which may be inserted a belt 22,

which also may be housed within recesses 16-17, 16'-17', and a shallow central recess connecting recesses 16-17.

By virtue of this arrangement, the two buoyant members 10, 11 can be moved apart as far as straps 14, 15 permit, and in their open position the side straps 18, 19, 18', 19' hang down at the sides reaching to about the waistline of the wearer and holding the belt in the proper position for being fastened onto the body, straps 14, 15 remaining directly under the arms.

When the two members 10, 11 have been spread apart, it is very easy to insert the device over the head and to slide it down to position, it being only necessary to fasten the belt 22 in order to retain it there. It will be understood that straps 14, 15 may previously have been adjusted to proper length causing the two upper portions of members 10, 11 to slightly press against the body of the wearer so as to be prevented from sliding down by friction, it being understood that the length of straps 14, 15, 18, 19, 18', 19' may have been adjusted in advance to suit.

It will be observed that when the device is thus adjusted in position as shown in Figs. 7, 8, 9, 10, the two buoyant members 10, 11 remain placed directly in front of the chest and at the rear of the shoulders respectively, lightening the upper part of the body so that the rest of the body can freely hang down and the general tendency will be for the body to remain in the water in a substantially vertical position. The head is held well above the water level, the upper surface of members 10, 11 also being somewhat above the level of the water.

It is therefore seen that the advantage possessed by life saving belts of the ordinary type of allowing complete freedom of movement of the arms and legs, is fully retained while on the other hand, the lifting force due to the buoyancy of the device is applied in the proper place and does not tend to interfere with the natural position of the immersed body.

In Figs. 6, 7 the two black marks 22, 23 represent the head and the liver respectively, these being the heaviest parts of the human body.

In Fig. 6 it will be seen that a life saving belt 24 of the ordinary type which is applied directly about the region of the liver may co-operate with the weight of the head in inducing a downward tilting movement of the upper part of the body.

In Fig. 7 the life saving device of my invention is shown applied to the upper part of the body thus causing the liver and other abdominal organs to actually lower the center of gravity of the body.

As stated, the two members 10, 11 may be retained in their closed position in any suitable manner. In the arrangement shown in

the drawings, the inner lower edge of member 11 is provided with a lid 25 which is adapted to interengage with a recess 26 provided along the inner lower edge of member 10 so as to form a detachable hinge-like connection therewith.

The upper surface of member 11 is equipped with a flap 27 mounted on longitudinal pivots at 28, said flap being adapted to be lowered over the upper surface 29 of member 10 and to be fastened to a catch 30 by means of a tongue 31 adapted to interlock therewith.

Flap 27 is equipped with a handle 32 by means of which the device may be carried, said handle assisting in producing in the device the general appearance of a hand bag.

Flap 27 as stated is tilttable about horizontal pivots 28 but is preferably tilttable to the rear to an inclined position only slightly beyond the vertical as shown in Figs. 2, 4, 5. As a result, said flap can be used as a head rest permitting of reclining the head rearwardly for the purpose of relieving fatigue.

This function is clearly illustrated in Figs. 8, 9. Insofar as described, the device efficiently fulfills and improves upon the function of an ordinary life saving belt, so that it considerably increases the chances of the wearer remaining afloat for an indefinite time. As stated before however, I have found in actual practice that thirst is quite frequently the direct cause of a person's death even though that person has succeeded in remaining afloat.

I therefore provide one of buoyant members 10, 11, preferably the front member 10, with a closed compartment 33 preferably located at the lower end thereof, said compartment being filled with thirst relieving liquid which may be drinking water. In practice however, I prefer to add to the water 10% pure alcohol and 10% of sugar such a combination being more effective in restoring strength than water alone.

Compartment 33 is, of course, water tight but is provided with a suction tube 34 reaching close to the bottom thereof and extending upwardly through the opening 35 in the upper surface 29 of the buoyant member, the projecting end of said tube being formed or equipped with a suction nipple 36 of the pacifier type.

As clearly shown in Figs. 7 and 10, said nipple is directly within reach of the mouth of the wearer, so that water can be sipped at intervals without any effort whatever.

In a similar manner the center portion of the lower end of the buoyant member 11 can be formed with a water tight chamber within which can be stored documents, money or other valuables, said chamber being controlled by a suitable lock 38.

Nipple 36 being made of rubber, is flexible and can be folded down within opening 35 as shown in Fig. 3 when flap 27 is lowered in

position, so that said nipple remains normally concealed from view.

The device can be easily expanded simply by releasing catch 30 after which it can be quickly inserted in position as explained.

It is obvious also that if a standard size device is made it may not be necessary to make the straps 14, 15, 18, 19, 18', 19' of an adjustable nature, although when the devices are intended for use in public places or on passenger ships, it is preferable to make these straps adjustable so that each person may adjust the device to his or her body in advance.

For the purpose of my invention it is not strictly necessary that a belt and straps connecting said belt to the buoyant members are used in connection with my device.

Although the two buoyant members are preferably in the nature of hollow chambers made out of sheet metal, providing individual rigid structures, it is also possible to make said buoyant members out of flexible waterproof material such as rubber, rubberized fabric and the like.

Likewise it is also within the scope of my invention to make said buoyant members out of cork or some other suitable material lighter than water.

It will be observed that when the body of the wearer is immersed into the water no material pressure against the body is exerted by the two buoyant members so that no interference with proper breathing results.

The various constructional details of my invention may vary to a certain extent from those shown without departing from the inventive idea; the drawings will therefore be understood as being intended for illustrative purposes only and not in a limiting sense.

Accordingly, I reserve the right to carry my invention into practice in all those ways and manners which may enter, fairly, into the scope of the appended claims.

I claim:

1. A device of the class described comprising front and rear watertight hollow members, connecting straps therebetween, a belt, and flexible connections between said belt and said members, at least one of said members being formed with a closed compartment adapted to hold a quantity of liquid, and a suction tube extending from said compartment to the front of the device, within convenient reach of the mouth of the wearer.

2. A device of the class described comprising front and rear watertight hollow members, connecting straps therebetween, a belt, and flexible connections between said belt and said members, said front member being provided with a closed compartment adapted to hold a quantity of liquid, and with a suction tube extending from said compartment to a point within convenient reach of the mouth of the wearer, and said rear member being

provided with a watertight lock controlled storage compartment.

3. A device of the class described comprising front and rear watertight hollow members, connecting straps therebetween, a belt, and flexible connections between said belt and said members, at least one of said members being formed with a closed compartment adapted to hold a quantity of liquid, and a suction tube extending from said compartment to the front of the device, within convenient reach of the mouth of the wearer, said compartment being located at the lower part of said member, so as to lower the center of gravity of the resulting structure.

4. A device of the class described comprising a collapsible structure consisting of front and rear buoyant members, flexible connecting straps therebetween, releasable means for securing said members to each other to form a single compact structure, and recesses within said members, adapted to receive said straps when said members abut against each other.

5. A device of the class described comprising a collapsible structure consisting of front and rear buoyant members, flexible connecting straps therebetween, releasable means for securing said members to each other to form a single compact structure, a belt, flexible connections between said belt and said members, and recesses within said members, adapted to receive said straps, belt, and flexible connections, when said members abut against each other.

6. A device of the class described comprising a collapsible structure consisting of front and rear buoyant members, flexible connecting straps therebetween, and a tiltable lid carried by said rear member, adapted to connect said members to each other to form a single compact structure, said lid being tiltable to an upwardly inclined position to the rear.

7. A device of the class described comprising a collapsible structure consisting of front and rear buoyant members, flexible connecting straps therebetween, and releasable means for securing said members to each other to form a single compact structure, said front member being provided with a closed compartment adapted to hold a quantity of liquid, and a suction tube extending from said compartment to a point within convenient reach of the mouth of the wearer.

8. A device of the class described comprising a collapsible structure consisting of front and rear buoyant members, flexible connecting straps therebetween, releasable means for securing said members to each other to form a single compact structure, a belt, flexible connections between said belt and said members, and recesses within said members, adapted to receive said straps, belt, and flexible connections, when said members abut against each

other, said front member being provided with a closed compartment adapted to hold a quantity of liquid, and a suction tube extending from said compartment to a point within convenient reach of the mouth of the wearer.

9. A device of the class described comprising a collapsible structure consisting of front and rear buoyant members, flexible connecting straps therebetween, releasable means for securing said members to each other to form a single compact structure, a belt, flexible connections between said belt and said members, recesses within said members, adapted to receive said straps, belt, and flexible connections, when said members abut against each other, and a head rest carried by said rear member, said front member being provided with a closed compartment adapted to hold a quantity of liquid, and a suction tube extending from said compartment to a point within convenient reach of the mouth of the wearer.

10. A device of the class described comprising a collapsible structure consisting of front and rear buoyant members, flexible connecting straps therebetween, a belt, flexible connections between said belt and said members, recesses within said members adapted to receive said straps, belt and flexible connections, when said members abut against each other, one of said members being provided with a closed compartment adapted to hold a quantity of liquid, and a suction tube extending from said compartment to a point within convenient reach of the mouth of the wearer, and a tiltable lid carried by said rear member, adapted to connect said members to each other to form a single compact structure, said lid being tiltable to an upwardly inclined position to the rear.
